UNITED STATES PATENT OFFICE

172,765

CHILD'S TOY

Max Reich, London, England, assignor to Combex
Limited, London, England, a British company

Application February 15, 1954, Serial No. 29,034

Claims priority, application Great Britain
November 4, 1953

Term of patent 7 years

(Cl. D34—2)

To all whom it may concern:

Be it known that I, Max Reich, a British subject, have invented a new, original, and ornamental Design for a Child's Toy, of which the following is a specification, reference being had to the accompanying drawing, forming part thereof.

Fig. 1 is a side view of a child's toy, showing my new design.

Fig. 2 is a plan view.

Fig. 3 is a front perspective view.

Fig. 4 is a rear bottom perspective view.

I claim:

The ornamental design for a child's toy, as shown.
